UNITED STATES PATENT OFFICE

100,358

DESIGN FOR A LAMP BODY OR SIMILAR ARTICLE OF MANUFACTURE

Bobby L. Baxley, Hensley, Ark.

Application June 14, 1935, Serial No. 57,275

Term of patent 14 years

To all whom it may concern:

Be it known that I, Bobby L. Baxley, a citizen of the United States of America, residing at Hensley, in the county of Saline and State of Arkansas, have invented a new, original, and ornamental Design for a Lamp Body or Similar Article of Manufacture, of which the following is a specification, reference being had to the accompanying drawing, wherein:

Figure 1 is a perspective view of the lamp body or similar article of manufacture, showing my new design.

I claim:

The ornamental design for a lamp body or similar article of manufacture as shown.

BOBBY L. BAXLEY.
